UNITED STATES PATENT OFFICE.

CHRISTIAN BECKER AND FRANK D. KLEINHEKSEL, OF HOLLAND, MICHIGAN.

AIR-HUMIDIFIER.

1,206,081.

Specification of Letters Patent. Patented Nov. 28, 1916.

Application filed March 8, 1916. Serial No. 82,974.

To all whom it may concern:

Be it known that we, CHRISTIAN BECKER and FRANK D. KLEINHEKSEL, citizens of the United States, residing at Holland, Michigan, have invented certain new and useful Improvements in Air-Humidifiers, of which the following is a specification.

This invention relates to an improvement in air humidifiers, for use in combination with heating furnaces.

The main objects of this invention are: First, to provide an improved air humidifier especially adapted to be used in connection with a hot air furnace and adapted to utilize a portion of the waste heat usually lost through the chimney, although the humidifier may be used to advantage in other systems. Second, to provide an improved air humidifier having suitable operating dampers wherein the humidity of the air arising in the furnace pipes may be regulated as desired or the amount of humidity may be regulated, no matter how delivered. Third, to provide improved means of abstracting waste heat from the products of combustion on their way to the chimney or smoke stack. Fourth, to provide an improved air humidifier having a suitable overflow means which provides for the circulation of the water when the same is heated, insuring the proper heating and evaporation.

Further objects, and objects relating to details and economies of construction and operation will definitely appear from the detailed description to follow.

We accomplish the objects of our invention by the devices and means described in the following specification.

The invention is clearly defined and pointed out in the claims.

A structure which is a preferred embodiment of our invention is clearly illustrated in the accompanying drawing, forming a part of this specification, in which:

Figure I is a side elevation of our humidifier showing the same connected to the smoke pipe and the sheet metal casing of a hot air furnace, the latter being shown in section and the dome of the furnace conveniently in full lines. Fig. II is an enlarged detail transverse section of our humidifier showing the arrangement of the various parts thereof, taken on the line 2—2 of Figs. I and III. Fig. III is a detail horizontal section through our humidifier, showing the arrangement of the piping therein, taken on

the broken line 3—3 of Fig. II. Fig. IV is an enlarged detail vertical section showing the arrangement of the piping within our humidifier, taken on line 4—4 of Fig. III. Fig. V is an enlarged detail vertical section of the slide means to facilitate the removal of the piping from the humidifier, taken on line 5—5 of Fig. I. Fig. VI is an enlarged detail horizontal section through the said slide means taken on line 6—6 of Fig. V. Fig. VII is an enlarged detail vertical section through our humidifier, showing the arrangement of the damper of the vapor chamber thereof, taken on line 7—7 of Fig. III. Fig. VIII is an enlarged detail vertical section showing a modified arrangement of the piping and the connection of the same to the water pan in our humidifier. Fig. IX is a detail transverse section of a modification of our humidifier showing the arrangement of the various parts, taken on line 9—9 of Fig. X. Fig. X is a detail horizontal section through the modified humidifier structure, taken on line 10—10 of Fig. IX.

In the drawing, similar reference characters refer to similar parts throughout the several views, and the sectional views are taken looking in the direction of the little arrows at the ends of the section lines.

Our humidifier is adapted to be used in connection with the ordinary hot air furnace consisting of the usual cast metal fire box 1, the radiator 2, from which leads the smoke pipe 3, having a check draft 4 therein. The furnace is covered by the usual side casing 5, the conical top casing 6, inverted cone deflector 7 and the various hot air pipes 8 lead therefrom.

Our humidifier is adapted to be connected to the smoke pipe 3 between the furnace casing 5 and the check damper 4, as shown in Fig. I, whereby the products of combustion from the furnace will have to pass through the said humidifier to heat and evaporate the water contained therein.

Referring to Fig. II, our humidifier consists of an outer casing 9 and an inner casing 10 between which casings is the heating flue space 11. On the lower side of casing 9 is an opening 12 embraced by the pipe 13 secured to said casing 9 and having the damper 14 therein. The spaces between the inner and outer casings are covered at their ends by the plates 15, see Figs. III and VIII, which are also provided with suitable central pipe flanges 16 to connect the humidifier

to the divided smoke pipe 3. The general shape of the casings are shown in Fig. II where the top of the same is wider than the casing body to facilitate evaporation.

5 Within the top of casing 10 is secured the water evaporating pan 17. The bottom of this pan is formed of a series of V-shaped longitudinal corrugations 18, thus giving a greater area of heating surface to the said pan to absorb the heat from the passing products of combustion. At the furnace end of said pan, the bottom of the same is formed into a transversely disposed rectangular header channel portion 18', see Fig. VIII, 10 in which terminates one end of the said V-shaped corrugations.

The top of our humidifier is adapted to inclose and cover casing 9 and preferably is raised at the center. The humidifier top is 20 double walled, comprising plates 19 and 20 between which is a suitable heat insulator 21, preferably asbestos wool. The said plates 19 and 20 have a depending outer flange 22 which is adapted to engage and tightly cover the top of casing 9. A discharge pipe 23 is suitably secured to the said plates by the collar 24. Pipe 23 is led from the humidifier through the furnace top casing 6 and discharges centrally against the cone deflector 7, as shown in Fig. I. Within the said discharge pipe is located a suitable damper 25. An opening 45 is provided to deliver from flue space 11 into the humidifying chamber above the pan.

35 From one side of the top of the humidifier extends the sheet metal hood 26, see Fig. VII, which is adapted to partially surround the smoke pipe 3, and has its bottom left open. Within the said hood is pivoted the damper 27 having the damper arm 28 secured thereto. Damper means 25 and said arm 28 are connected to be operated by chains or cords 29, 29'. The upper portion of the side wall of the casing 10 is left open 40 at 30 so as to permit heated air to enter the humidifier from the said hood, which will, of course, regulate the humidity. The quantity of air admitted to the humidifier may thus be regulated by the dampers 14 45 or 27 and the passage of humidified air may be regulated by damper 25.

A water tank 31 having a suitable cover 32 thereon is secured by the straps 33 to the said casing 9. Water pan 17 and tank 50 31 are connected by the nipple 34, a water tight connection between the two being made by suitable nuts and washers, as shown in Fig. II. From the bottom of tank 31 leads a supply pipe 35. Said pipe 35 is shaped as 55 shown in Fig. III, the same passing through the end plates 15, then forming a bend 35' toward the furnace inside of casing 10. This bend is connected to the water pan by the vertical pipes 36 and 37, see Figs. III and 60 IV, pipe 36 connecting the water pan at the

center thereof while pipe 37 connects the same at the header channel portion 18' thereof. A suitable drain cock 38 is installed in pipe 35 so as to drain the water pan and tank when desired. Water is admitted to said tank 31 by the float controlled valve 39, which is controlled by float 42, Figs. I and II, which connects to the outside water circuit by pipe 40 controlled by valve 41. The level of water to be maintained in the water pan is shown in Fig. II, where the same is slightly below the nipple 34, float 42 being so set to maintain this level. To facilitate the removal of pipe 35 and pan 17, plate 15 is slotted at 43, the 75 edges of which are bent and permits the slide plate 44 to open and close the same, see Fig. VI.

It will be observed that when the furnace is in operation and water has been admitted 80 to our humidifier, the waste products of combustion will pass into the chamber formed by the casing 10 and heat the water in the said water pan 17. The vapor thus generated will rise up through the discharge 85 pipe 23 into the furnace casing against the cone deflector 7. The humidified air will mix with the hot air from the furnace and thence pass up through the furnace pipes 8. The degree of humidity produced may be 90 regulated by the damper 14 in the pipe 13, wherein outside air will be drawn through the said pipe and into the flue space 11 and will then mix with the vapors. The said flue space therefore serves to heat this air 95 and thereby prevents any condensation of the said vapors. The amount of vapor rising in the said pipe 23 is regulated by the damper 25 therein.

The circulation from the supply tank 31 100 is through pipe 35 which connects to the horizontally disposed loop 35' disposed in the furnace end of the casing and smoke pipe. This is slightly inclined and connected to and delivers upwardly through pipe 37, and the circulation is induced by the heating of the loop 35' which takes water from the header channel 18' and circulates it downwardly and then upwardly to the pipe 36, so that the water at the highest 105 temperature delivers out through the vertical pipe 36 and spreads into the pan at the highest point, and evaporation is thus greatly facilitated.

The connection we have indicated is much 110 to be preferred, but very good results may be obtained by making the connections as appear in Fig. VIII, permitting the supply pipe 35 to deliver upwardly through pipe 36' into the pan and provide an independent circulating pipe system comprising the downwardly-extending pipe 37' from the bottom of the header channel 18', thence looping toward the furnace horizontally and upwardly at 35'' and delivering out at the 115 120 125 130

top at 36", as seen in Fig. VIII. This circulation also insures the delivery of the hottest water at the upper surface, where, of course, it will evaporate most readily. In the event 5 that the water tends to boil, of course the steam in it will cause it to expand until the water will overflow from the nipple 34 into the supply tank 31, and when the hot water flows through at that point the colder water 10 in the tank 31 will be displaced and be supplied into the vaporizing pan through pipes 35, 36.

The quantity of dry air admitted into the 15 humidifying chamber for circulation is controlled by the dampers 14 and 27 already described. Where our humidifier is used with other heating apparatus than a hot air furnace, a pipe can deliver directly up from the top of the same to any apartment to be 20 humidified, as indicated by dotted lines in Fig. I.

In Figs. IX and X we show a modification of our improved humidifier, in which in place of the corrugated pan 18 we corrugate a section of pipe at 50, and surround the same with a casing 51 which forms an annular water chamber 52, see Fig. IX. The heated products of combustion circulating within the same passes into the corrugations 30 of the pipe 50 and heats the surrounding water. The tank 31, pipe 35 and loop 35' are identical with those illustrated in the preferred form, the loop 35' connecting to an upwardly extending pipe section 60 delivering into the top of the annular reservoir, as seen in Figs. IX and X. This structure is suspended by the bands 54, as distinguished from the supporting rods 40', 40' of the preferred structure. It is desirable 40 to insulate casing 51 by a suitable heat insulator 53 held thereto by bands 54. The top has an inturned flange 22' to fit the vaporizer tank.

Having thus described our invention, 45 what we claim as new and desire to secure by Letters Patent is:

1. The combination of a furnace having an inclosing casing, a smoke pipe leading therefrom, a check damper for said smoke 50 pipe, a vapor casing disposed to be heated by said pipe and to the furnace side of said check damper, damper means for admitting air to said vapor casing, a supply tank for delivering water to the said vapor casing, 55 a float valve for regulating and controlling the level of the water in said vapor casing, a conduit leading from said vapor casing into the said furnace casing for humidifying the air delivered from said furnace, and 60 damper means in the said conduit for regulating the delivery of the vapor.

2. The combination of a furnace having an inclosing casing, a smoke pipe leading therefrom, a vapor casing disposed to be heated 65 by said pipe, damper means for ad-

mitting air to said vapor casing, a supply tank for delivering water to the said vapor casing, a float valve for regulating and controlling the level of the water in said vapor casing, a conduit leading from said vapor 70 casing into the said furnace casing for humidifying the air delivered from said furnace, and damper means in the said conduit for regulating the delivery of the vapor.

3. The combination of a furnace having 75 an inclosing casing, a smoke pipe leading therefrom, a vapor casing disposed to be heated by said pipe, means for admitting air to said vapor casing, a supply tank for delivering water to the said vapor casing, a 80 float valve for regulating and controlling the level of the water in said vapor casing, a conduit leading from said vapor casing into the said furnace casing for humidifying the air delivered from said furnace, and 85 damper means in the said conduit for regulating the delivery of the vapor.

4. The combination of a furnace having an inclosing casing, a smoke pipe leading 90 therefrom, a vapor casing disposed to be heated by said pipe, means for admitting air to said vapor casing, a supply tank for delivering water to the said vapor casing, a float valve for regulating and controlling the level of the water in said vapor casing, 95 and a conduit leading from said vapor casing into the said furnace casing for humidifying the air delivered from said furnace.

5. The combination of a furnace having an inclosing casing, a smoke pipe leading 100 therefrom, a vapor casing disposed to be heated by said pipe, means for admitting air to the said vapor casing, a supply tank for delivering water to the said vapor casing, a conduit leading from said vapor casing 105 into the said furnace casing for humidifying the air delivered from said furnace, and damper means in the said conduit for regulating the delivery of the vapor.

6. The combination of a furnace having an inclosing casing, a smoke pipe leading therefrom, a vapor casing disposed to be heated by said pipe, means for admitting air to said vapor casing, a supply tank for delivering water to the said vapor casing, and a conduit leading from said vapor casing into 115 the said furnace casing for humidifying the air delivered from said furnace.

7. The combination of a furnace having an inclosing casing, a smoke pipe leading therefrom, a vapor casing disposed to be heated by said pipe, damper means for admitting air to said vapor casing, a conduit leading from said vapor casing, and damper means in the said conduit for regulating the delivery of the vapor.

8. The combination of a furnace having an inclosing casing, a smoke pipe leading therefrom, a vapor casing disposed to be heated 120 by said pipe, means for admitting air to said pipe,

- vapor casing, a conduit leading from said vapor casing, and damper means in the said conduit for regulating the delivery of the vapor.
5. 9. The combination of a furnace having an inclosing casing, a smoke pipe leading therefrom, a vapor casing disposed to be heated by said pipe, means for admitting air to said vapor casing, and a conduit leading from
- 10 said vapor casing.
10. The combination of a furnace, a smoke pipe leading therefrom, a vapor casing disposed to be heated by said pipe, damper means for admitting air to said vapor casing, a supply tank for delivering water to said vapor casing, a float valve for regulating and controlling the level of the water in said vapor casing, a conduit leading from said vapor casing, and damper means in the
- 15 20 said conduit for regulating the delivery of the vapor.
11. The combination of a furnace, a smoke pipe leading therefrom, a vapor casing disposed to be heated by said pipe, means for admitting air to said vapor casing, a supply tank for delivering water to the said vapor casing, a float valve for regulating and controlling the level of the water in said vapor casing, a conduit leading from said vapor casing, and damper means in the said conduit for regulating the delivery of the vapor.
12. The combination of a furnace, a smoke pipe leading therefrom, a vapor casing disposed to be heated by said pipe, means for admitting air to said vapor casing, a supply tank for delivering water to the said vapor casing, and a conduit leading from said vapor casing.
13. The combination of a furnace, a smoke pipe leading therefrom, a vapor casing disposed to be heated by said pipe, damper means for admitting air to said vapor casing, a conduit leading from said vapor casing, and damper means in the said conduit
- 40 45 for regulating the delivery of the vapor.
14. The combination of a furnace, a smoke pipe leading therefrom, a vapor casing disposed to be heated by said pipe, means for admitting air to said vapor casing, and a conduit leading from said vapor casing.
15. In a humidifier, the combination with a smoke pipe delivering the heated products of combustion, a casing having connections in said pipe for the passage of said products of combustion therethrough, a vaporizer pan with a bottom containing longitudinal corrugations and a header channel connecting the said corrugations disposed within the casing, a supply tank, a float valve for controlling and regulating the height of the water delivered to said vaporizing chamber and a connection overflow passage between said pan and supply tank whereby the pan
- 50 55 overflows to said tank, a pipe from said supply tank looped forwardly toward the furnace side of said vaporizer and upwardly and delivering into the said vaporizer pan, a pipe connection from the bottom of the header channel to the said supply for insuring circulation, and a delivery pipe from said vaporizer with damper for controlling the same, coacting as specified.
16. In a humidifier, the combination with a smoke pipe delivering the heated products of combustion, a casing having connections in said pipe for the passage of said products of combustion therethrough, a vaporizer pan with a bottom containing longitudinal corrugations and a header channel connecting the said corrugations disposed within the
- 60 65 casing, a supply tank, a float valve for controlling and regulating the height of the water delivered to said vaporizing chamber and a connection overflow passage between said pan and supply tank whereby the pan overflows to said tank, a pipe from said supply tank looped forwardly toward the furnace side of said vaporizer and upwardly and delivering into the said vaporizer, a pipe connection from the bottom of the header channel to the said supply for insuring circulation, and a delivery pipe from said vaporizer with damper for controlling the same, coacting as specified.
17. In a humidifier, the combination with a smoke pipe delivering the heated products of combustion, a casing having connections in said pipe for the passage of said products of combustion therethrough, a vaporizer pan with a bottom containing longitudinal corrugations and a header channel connecting the said corrugations disposed within the
- 70 75 80 85 90 95 100 105 110 115 120 125 130 said casing, a supply tank, a float valve for controlling and regulating the height of the water delivered to said vaporizing chamber and a connection overflow passage between said pan and supply tank whereby the pan overflows to said tank, a pipe from said supply tank looped forwardly toward the furnace side of said vaporizer and upwardly and delivering into the said vaporizer pan, a pipe connection from the bottom of the header channel to the said supply for insuring circulation, and a delivery pipe from said vaporizer with damper for controlling the same, coacting as specified.
18. In a humidifier, the combination with a smoke pipe delivering the heated products of combustion, a casing having connections in said pipe for the passage of said products of combustion therethrough, a vaporizer pan disposed within the casing, a wall surround-

ing said vaporizer forming a heating flue passage connecting above the vaporizer pan, an intake opening at the bottom thereof with a damper for controlling the same, and 5 a delivery pipe from said vaporizer with damper for controlling the same, coacting as specified.

19. In a humidifier, the combination with a smoke pipe delivering the heated products 10 of combustion, a casing having connections in said pipe for the passage of said products of combustion therethrough, a vaporizer pan disposed within the casing, and a delivery pipe from said vaporizer with damper for 15 controlling the same, coacting as specified.

20. In a humidifier, the combination with a smoke pipe delivering the heated products of combustion, a casing having connections in said pipe for the passage of said products 20 therethrough, a vaporizer pan with bottom containing longitudinal corrugations and a header channel connecting the said corrugations disposed within the said casing, and a pipe connecting the said header channel extending 25 downwardly and then looped forwardly and upwardly and delivering at the water level within said vaporizing pan, as specified.

21. In a humidifier, the combination with 30 a smoke pipe delivering the heated products of combustion, a casing having connections in said pipe for the passage of said products therethrough, and a vaporizer pan with bottom containing longitudinal corrugations 35 and a header channel connecting the said corrugations disposed within the said casing, as specified.

22. In a humidifier, the combination with a smoke pipe delivering the heated products 40 of combustion, a casing having connections in said pipe for the passage of said products therethrough, and a vaporizer pan with bottom containing longitudinal corrugations disposed within the said casing, as specified.

23. In a humidifier, the combination with 45 a smoke pipe delivering the heated products of combustion, a casing having connections in said pipe for the passage of said products therethrough, a vaporizer pan within the said casing, a supply tank, a float valve for 50 regulating the height of water delivered into and from said supply tank, and a passage at substantially the water level connecting the vaporizer pan and the supply tank so that on the expansion of the water to be 55 heated it will overflow into the supply tank and displace the water into the vaporizer pan, as specified.

24. In a humidifier, the combination with 60 a smoke pipe delivering the heated products of combustion, a casing having connections in said pipe for the passage of said products therethrough, a vaporizer pan, and a coil connected to said vaporizer pan looped forwardly away from the chimney side of said 65 connection and delivering upwardly and into the pan at substantially the water level to insure circulation of the water and the rapid evaporation of the same, as specified.

25. In a humidifier, the combination with 70 a vaporizer pan disposed to be heated by the products of combustion, a supply tank, a float valve for regulating the height of water delivered into and from said supply tank, and a passage at substantially the water level connecting the vaporizer pan and the supply tank so that on the expansion of the water to be heated it will overflow into the supply tank and displace the water into 75 the vaporizer pan, as specified.

In witness whereof, we have hereunto set our hands and seals in the presence of two witnesses.
